UNITED STATES PATENT OFFICE.

CATHERINE SHIELS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 14,921, dated March 25, 1884.

Application filed February 13, 1884. Term of patent 3½ years.

To all whom it may concern:

Be it known that I, CATHERINE SHIELS, of the city, county, and State of New York, have invented and produced a new and original Design 5 for a Pattern of a Girl's Costume, (numbered 9,128;) and I do hereby declare that the engraved prints accompanying this specification convey to any one accustomed to using paper patterns a clear understanding of how a garment made up by the pattern will appear.

The design shows deep, loose-fitting fronts, flaring from the waist-line to the tops of the shoulders, over a narrow-pointed vest, and also below the waist-line, over a plain skirt portion;

a half-fitted back, with a double box-plait 15 down its center; short pannier draperies meeting below the vest, and exhibiting draping plaits in their front and back edges; coat-sleeves, and a standing neckband.

What I claim as my invention, and desire to 20 secure by Letters Patent, is—

The design for a girl's costume, as shown in the engraved prints accompanying this specification.

CATHERINE SHIELS.
